[57] CLAIM

The ornamental design for a holder for assorted desk articles, as shown and described.

DESCRIPTION

FIG. 1 is a top plan view of a holder for assorted desk articles showing my new design;

FIG. 2 is a front elevational view thereof;

FIG. 3 is a side elevational view, the opposite side being a mirror image thereof;

FIG. 4 is a bottom plan view thereof; and

FIG. 5 is a cross-sectional view taken along line 5—5 of FIG. 1.
